United States Patent

Des. 236,399
Patented Aug. 26, 1975

236,399

CABINET

Ronald W. Rubin, Riverdale, N.Y., assignor to
Living Walls Inc., Bronx, N.Y.

Filed Sept. 26, 1973, Ser. No. 400,874

Term of patent 14 years

Int. Cl. D6—04

U.S. Cl. D6—170

FIG. 1

FIG. 2

FIG. 3

FIG. 4

FIG. 1 is a top plan view of a cabinet showing my new design;

FIG. 2 is a front elevational view;

FIG. 3 is a right side elevational view; and

FIG. 4 is a front, top and left side perspective view. The rear of the cabinet is plain and unornamented.

I claim:

The ornamental design for a cabinet, as shown and described.
